E. ROSENBAUM,
PROTECTOR FOR MAGAZINES AND THE LIKE,
APPLICATION FILED AUG. 3, 1917.

Patented Dec. 11, 1917.

UNITED STATES PATENT OFFICE.

EDWARD ROSENBAUM, OF NEW YORK, N. Y.

PROTECTOR FOR MAGAZINES AND THE LIKE.

1,249,507.

Specification of Letters Patent. Patented Dec. 11, 1917.

Application filed August 3, 1917. Serial No. 184,210.

To all whom it may concern:

Be it known that I, EDWARD ROSENBAUM, a citizen of the United States, and a resident of New York city, in the county of New York and State of New York, have invented certain new and useful Improvements in Protectors for Magazines and the like, of which the following is a specification.

The invention pertains more particularly to attachable and detachable means for application to the back corner edge portions of magazines or other delicately bound pamphlets, books and the like, together with auxiliary front and back protecting covers of stiff paper or the like, applicable to said means, the whole being for the purpose of preventing undue wear on the regular covers of the magazines or the like during their customary use. Magazines ordinarily have paper covers secured thereto, and in use, especially in libraries, reception halls and the like, the covers of the magazines become torn, and the magazine itself becomes ragged and worn in its cover portions and at its back corner edges, and to remedy this situation I have provided my invention, which comprises protecting members to be applied to the back corner edge portions of magazines and auxiliary protecting front and back cover members corresponding in size with the front and back permanent covers of the magazine and to be secured on the magazine by the aforesaid corner edge protecting members.

The protector of my invention comprises two coöperating features, one being angle members for each back corner edge portion of the magazine and preferably of the character disclosed in Letters Patent granted to me July 3, 1917, No. 1,231,942, with certain modified or added features of construction hereinafter referred to, and the second being auxiliary front and back covers to be applied against the front and back permanent covers of the magazine and adapted to be firmly secured in position by the aforesaid angle members applied to the back corner edge portions of the magazine.

The invention will be fully understood from the detailed description hereinafter presented, reference being had to the accompanying drawings, in which:

Figure 1 is a perspective view of a magazine equipped with the protectors of my invention;

Fig. 2 is a back edge view of a magazine

equipped with the protectors of my invention;

Fig. 3 is a face elevation of a portion of the same;

Fig. 4 is a top view of the upper back portion of the same, on an enlarged scale;

Fig. 5 is a vertical section through a portion of the same, on an enlarged scale, taken on the dotted line 5—5 of Fig. 3;

Fig. 6 is a vertical section through the upper back portion of the magazine and auxiliary front and back covers, taken on the dotted line 6—6 of Fig. 3, and is presented to illustrate the lips on the upper and lower ends of the back corner protector members which pass between and embrace a number of the leaves of the magazine;

Fig. 7 is a horizontal section through a portion of the magazine and its protecting features, taken on the dotted line 7—7 of Fig. 3;

Fig. 8 is a horizontal section through the same, taken on the dotted line 8—8 of Fig. 2;

Fig. 9 is a detached perspective view, partly broken away of one of the auxiliary covers, and

Fig. 10 is a detached perspective view of one of the angle members of the rear edge corner protectors.

In the drawings, 10 designates a magazine as a whole, 11 the leaves thereof, and 12 auxiliary front and back cover members applied to the front and back faces of the magazine and which are coextensive with the usual outer cover pages of the magazine. The customary cover on a magazine is of sufficient length to extend over both the front rear and back surfaces of the magazine, and in the drawings 13 indicates the usual cover material extending across and secured to or against the back edges of the leaves 11. The magazine 10 is simply a magazine of ordinary character, such as issued monthly by various publishers, and is presented to illustrate one type of paper covered book to which my invention is applicable.

The protector of my invention comprises front and back corresponding auxiliary cover members 12 to be applied against the front and back members of the usual cover 13 on a magazine or the like, in combination with protectors for the back corner edge portions of the magazine and which are utilized as means for securing said auxiliary front and back cover members to the magazine, the

whole coöperating to protect not only the back corner members of the magazine but also the customary front and back permanent covers thereof against injury during the proper use of the magazine.

5 The front and back cover members 12 will be formed of stiff paper and have a crease or weakened line 14 extending vertically along the outer edge thereof so as to permit said 10 cover members to be easily opened outwardly without any necessity of the same being additionally creased, and said front and back cover members 12 are also formed at 15 convenient points near their outer or rear edges with vertical openings 15 to receive lips connected with the corner protector members and which lips secure said front and back auxiliary cover members in rigid position on the magazine.

20 The back corner edge protectors for the magazine are provided with lips 16 to enter the openings 15 in the front and back auxiliary cover members 12 and secure said members 12 on the magazine, and aside from 25 the presence of the lips 16 the back corner edge protectors correspond substantially with the protector shown and described in the aforesaid Letters Patent granted to me.

The back corner edge protectors comprise 30 two upper parallel members 17, 18, two lower parallel members 19, 20 and a spring 21 which ties together the inner ends of the members 17, 18 and serves to bind said ends of said members against the inner ends of 35 the members 19, 20, as well as to bind all of said members at their inner portions against the magazine. The members 17, 18 correspond with each other and the members 19, 20 correspond with each other and in

40 many respects correspond with the members 17, 18. The members 17, 18 and 19, 20 are reversely formed, being rights and lefts, so as to adapt them to the right and left hand edges of the back of the magazine, and pref- 45 erably said members are formed of sheet metal and then nickel plated. The mem- bers 17, 18 are each in one integral piece and of right angle formation so as to engage the back corner edges of the magazine, and

50 said members 17, 18 at their upper ends are formed integrally with inwardly turned members or hook extensions 22 which extend downwardly and are adapted to pass be- 55 tween the leaves of the magazine inwardly from the covers thereof and embrace the upper outer corners of the covers and a series of the leaves 11, as probably more clearly illustrated in Fig. 6, and whereby the upper ends of the members 17, 18 become securely

60 attached to the magazine and prevent the magazine at those points from being torn outwardly. The outer faces of the members 17, 18 are formed with longitudinal hollow beadings or corrugations 23 which are open 65 at their inner ends, and preferably the inner

ends of said members 17, 18 are flared outwardly to a slight extent, as at 24, so as to conveniently admit or pass over the inner ends of the members 19, 20.

The members 19, 20 are also each in one 70 integral piece and of right angle formation, and at their lower ends said members 19, 20 are formed integrally with inwardly turned members or hook extensions 25 which extend upwardly and may be moved upwardly 75 between the leaves of the magazine inwardly from the covers thereof so as to embrace the lower outer corners of the covers and a series of the leaves 11 correspondingly with the action of the upper members or 80 hook extensions 22. The members 19, 20 at their lower ends correspond with the upper end portions of the members 17, 18, except that the lower end portions of the members 19, 20 are applied upwardly on the mag- 85 azine, while the members 17, 18 at their upper end portions are applied downwardly on the magazine, and in both instances the outer ends of the said members become attached to the magazine and protect the 90 magazine at the ends of its back corner portions.

The members 19, 20 are formed with out- 95 wardly projecting hollow longitudinal beadings or corrugations 26 which serve as ribs to interlock with the hollow beadings of the members 17, 18. Each member 19, 20 has a rib 26 and each member 17, 18 has a hollow bead 23, and when the members 17, 18 are slid upon the members 19, 20, or the 100 members 19, 20 are slid beneath the members 17, 18, the ribs 26 enter the hollow beadings 23 and serve to aid in locking the upper and lower members of the back corner protector together and to facilitate the final securing 105 of the members of the protector firmly upon the magazine.

The rear corner protector members 17, 18, 110 19, 20 at their outer end portions effectually protect the outer back corners of the mag- azine, and the flanges formed by the right angle shape of said members in cross-section enable said members to embrace and protect the contiguous back corner longitudinal edges of the magazine.

115 The spring 21 corresponds exactly with a similar spring shown in my aforesaid Letters Patent, and it serves with the members 17, 18 and 19, 20 as a clamp whereby the protector becomes permanently held against the magazine. The spring 21 may vary in form and construction, as indicated in the aforesaid Letters Patent.

A new feature connected with the mem- 120 bers 19, 20 resides in the upper and lower 125 lips 16 which are cut from the metal of said members and pressed inwardly. The lips 16 are preferably of slightly curved outline and project inwardly and rearwardly, and when the corner protectors are on the magazine 130

the auxiliary covers 12 are slipped below the corner protectors until the openings 15 in said auxiliary covers pass upon and receive the lips 16, said lips, coöperating with the 5 openings 15, serving to retain the auxiliary covers 12 in fixed position on the magazine. The corner members 19, 20 may be applied on the magazine and the covers 12 then applied and caught on the lips 16, and there- 10 after the members 17, 18 may be applied to the magazine, the whole then being complete; or the members 17, 18, 19, 20 may all be applied to the magazine and the edges of the auxiliary covers 12 slipped below said 15 members until their openings 15 become interlocked with the lips 16 of the members 19, 20. The auxiliary covers 12 will protect the back and front faces of the magazine, and when they become soiled they may be 20 removed and fresh covers supplied in their stead.

I preferably make use of a split spring ring 27 at the upper rear corner of the magazine, the ends of the ring being projected 25 through openings 28 in the members 17, 18 and firmly binding against the upper rear corner portions of the auxiliary covers 12. The spring ring 27 aids in binding the auxiliary covers 12 in position, and affords 30 means by which the magazine may be suspended from a hook or the like. The ring 27 also aids in preventing the back of the magazine from being sprung outwardly to that extent which might tend to split the 35 upper end of the same. The ring 27 and the spring 21 are both under tension when the members of the protector are on the magazine.

The members 17, 18, 19, 20 slidably en- 40 gage one another at their inner ends, and this is desirable since it permits the members 17, 18 to be adjusted to books varying in height. It is preferable that the adjustment of the corner protectors to books vary- 45 ing in height be accomplished by the movement of the members 17, 18, since the lips 16 on the members 19, 20 should always stand in a fixed position, so as to enter the openings 15, provided in the auxiliary covers 12. 50 My present invention is not limited in all of the details of the corner members 17, 18, 19, 20, since these details may be modified without departing from the spirit of my invention, which resides more particularly in 55 corner members of any suitable character having the lips 16 and in the auxiliary cover sections 12 to be engaged and held in position by the corner members and the said lips 16 thereof.

60 What I claim as my invention and desire to secure by Letters-Patent, is:

1. A protector for magazines and the like comprising members adapted to the back corner edges of the magazine, means for 65 detachably securing said members in posi-

tion, and an auxiliary cover sheet to be held at its rear edge portion below and by one of said members, said member having inwardly projecting lips and said sheet openings to receive said lips, for securing said 70 sheet in position.

2. A protector for magazines and the like comprising members adapted to the back corner edges of the magazine, means for 75 detachably securing said members in position, and front and back auxiliary cover sheets to be held at their rear edges below said members, said members having inwardly projecting parts to engage and secure 80 said sheets.

3. A protector for magazines and the like comprising members adapted to the back corner edges of the magazine, means for detachably securing said members in position, front and back auxiliary cover sheets 85 to be held at their rear edges below said members, said members having inwardly projecting parts to engage and secure said sheets, and a split spring ring having its 90 ends projected through openings in said members and against said cover sheets.

4. A protector for magazines and the like comprising right angle upper and lower members adapted to the back corner edges 95 of the magazine, means for binding the inner portions of said members against the magazine, and auxiliary cover sheets to be held at their rear edges below said members, the upper ends of the upper members and the lower ends of the lower members hav- 100 ing hooked extensions to embrace said auxiliary sheets and the main covers and a series of the leaves of the magazine, and one pair of said members having inwardly projecting parts to engage and secure said auxiliary 105 cover sheets.

5. A protector for magazines and the like comprising right angle upper and lower members adapted to the back corner edges 110 of the magazine, means for binding the inner portions of said members against the magazine, and auxiliary cover sheets to be held at their rear edges below said members, the upper ends of the upper members and the lower ends of the lower members hav- 115 ing hooked extensions to embrace said auxiliary sheets and the main covers and a series of the leaves of the magazine, one pair of said members having inwardly projected lips, and said auxiliary cover sheets having 120 openings adjacent to their rear edges to receive said lips, for securing said sheets in position.

6. A protector for magazines and the like comprising right angle upper and lower 125 members adapted to the back corner edges of the magazine, means for binding the inner portions of said members against the magazine, and a split spring ring having its ends projected through openings in said 130

upper members and against the magazine, the upper ends of the upper members and the lower ends of the lower members having hooked extensions to embrace the covers and a series of the leaves of the magazine.

7. A protector for magazines and the like comprising right angle upper and lower members adapted to the back corner edges of the magazine, means for binding the inner portions of said members against the magazine, and an auxiliary cover sheet adapted to one face of the magazine and to be held at its rear edge below the said members at said face and one of which has in-

wardly projecting parts to engage and secure said sheet, the upper ends of the upper members and the lower ends of the lower members having hooked extensions to embrace the covers and a series of the leaves of the magazine.

Signed at New York city, in the county of New York and State of New York, this 1st day of August, A. D. 1917.

EDWARD ROSENBAUM.
